UNITED STATES PATENT OFFICE.

GUSTAV L. SCHOETTLER, OF STE. GENEVIEVE, MISSOURI.

SACK-HOLDER.

1,070,847.

Specification of Letters Patent. Patented Aug. 19, 1913.

Application filed May 19, 1913. Serial No. 766,768.

To all whom it may concern:

Be it known that I, GUSTAV L. SCHOETTLER, a citizen of the United States, residing at Ste. Genevieve, in the county of Ste. Genevieve and State of Missouri, have invented new and useful Improvements in Sack-Holders, of which the following is a specification.

The invention relates to sack holders, and 10 has for its primary object to provide a holder of this type wherein the mouth of a sack will be stretched open and sustained in such position so that the filling of the sack can be accomplished in a convenient manner 15 without requiring the attention and the hand opening thereof by a person or attendant.

Another object of the invention is the provision of a sack holder in which the sack can be opened and suspended therefrom 20 from a post or other stationary support, the weight of the contents of the sack serving to sustain the holder extended and thereby prevent the closing of the mouth of the sack during the filling of the same.

25 A further object of the invention is the provision of a sack holder which is capable of engaging the mouth edge of sacks of different sizes and to automatically open the same whereby the sack can be conveniently 30 filled without possibility of the mouth closing.

A still further object of the invention is the provision of a sack holder which is extremely simple in construction, thoroughly 35 reliable and efficient in its purpose, and inexpensive in manufacture.

With these and other objects in view, the invention consists in the construction, combination, and arrangement of parts as will 40 be hereinafter fully described, illustrated in the accompanying drawing, and pointed out in the claim hereto appended.

In the drawing:—Figure 1 is a perspective view of a sack showing the holder constructed in accordance with the invention in 45 position for opening the mouth of the sack and suspending it from a stationary support. Fig. 2 is a side elevation of the holder when folded. Fig. 3 is a top plan view of thereof. Fig. 4 is a perspective view of the holder extended with the sack removed. Fig. 5 is a fragmentary detail perspective view of the break joint and latch of one 50 of the arms of the holder.

55 Similar reference characters indicate cor-

responding parts throughout the several views in the drawing.

Referring to the drawing by numerals, 5 designates a sack, which is of the ordinary well-known construction, adapted to be connected to the holder presently described.

The holder comprises a suspension bar or hanger 6 formed at its upper end with a pointed hook 7, the latter adapted to be driven into a post or other stationary support at any desirable point thereof for the mounting of the hanger thereon. Swingingly connected to the lower end of the hanger 6 are arms 8, one of which has integrally formed therewith a right angular 70 terminal branch 9, while the other carries a swinging branch 10 which is connected thereto by means of a pivot 11, the said branch 10 being formed with a right angular portion corresponding to the branch 9. 75 These branches 9 and 10 are provided with spurs 12 projecting outwardly therefrom, and the arms 8 being pivoted at 13 to the said hanger 6 for the spreading apart or bringing together of the same in a manner 80 presently described.

Formed in the hanger 6 is an elongated slot 14 provided with a terminal offset notch 15 communicating therewith, and in this slot is slidably engaged the shank of a stud 16 85 which is adapted to enter the notch 15, and pivotally connects together a pair of links 17 which are connected to the arms 8 by means of pivots 18, these links being designed as spreaders for separating the arms on the 90 displacement of the stud 16 in the slot 14. One of the pivots 18 serves as a keeper for a latch member 19 which is pivoted at 20 to the branch 10, and is formed with a notch 21 providing a locking bill 22, the said notch 95 21 receiving the stud portion of the pivot 18 adjacent to the branch 10 so that the bill 22 will lock with the said pivot 18 and thereby hold the branch 10 rigid and against swinging movement so that on the spreading 100 of the branches 9 and 10 the same can be brought in position for engagement with the mouth edge of the sack 5 for suspending it from the holder.

The latch member 19 is formed with a handle 23 so that it can be readily manipulated for releasing the same to permit the swinging of the branch 10 for the dumping of the sack should the occasion require.

When the stud 16 is moved in the slot 110

14 to engage in the notch 15 the arms 8 will be brought together, which is the normal position thereof when the holder is not in use.

5 In the use of the holder the branches 9 and 10 are brought into position so that the spurs 12 will engage in the mouth edge of the sack at opposite points thereof as shown in Fig. 1 of the drawing. Now, on the spreading of 10 the arms 8 apart the mouth of the sack 5 will be opened and on the filling of the said sack the weight of its contents will sustain the mouth thereof fully open and the body of the sack will be stretched taut, it being understood of course that the latch member 19 is engaged with the pivot 18 so as to prevent the swinging of the branch 10. The hanger 6 of the holder is fastened upon a post or other stationary support by engaging 20 the hook 7 therein so that the sack will be suspended from the holder and the mouth thereof opened for the convenient filling of the same. Should it be desired to dump the sack it is only necessary to release the latch member 19 from engagement with the pivot 16 which permits the swinging of the branch 10 to the position shown in Fig. 5, whereupon the contents of the sack 5 can be readily dumped therefrom as the branch 9

will hold the sack to permit the dumping of 30 the same by lifting it from the bottom thereof, or its closed end.

From the foregoing it is thought that the construction, and manner of operation of the device will be clearly understood, and 35 therefore a more extended explanation has been omitted.

What is claimed is:—

A sack holder comprising a hanger having 40 a slot therein, a pair of arms pivotally connected to one end of the hanger, one of said arms being formed in two parts pivotally connected together, means on the arm for engagement with a sack, links pivotally connected to the arms and also pivotally connected together, the pivot connecting the links being slidably engaged in the slot in the hanger, and means carried by one part of the said two-part arm and engageable with the other part thereof for locking 45 the same in alinement with each other.

In testimony whereof I affix my signature in presence of two witnesses.

GUSTAV L. SCHOETTLER.
